UNITED STATES PATENT OFFICE.

CORNELIUS B. CORCORAN, OF NEW YORK, N. Y., ASSIGNOR TO UNDERWOOD TYPE-WRITER COMPANY, OF NEW YORK, N. Y., A CORPORATION OF DELAWARE.

TYPE-BAR REST.

Application filed July 21, 1922. Serial No. 576,416.

To all whom it may concern:

Be it known that I, CORNELIUS B. CORCORAN, a citizen of the United States, residing in borough of the Bronx, in the county of the Bronx, city and State of New York, have invented certain new and useful Improvements in Type-Bar Rests, of which the following is a specification.

This invention relates, primarily, to type-writing machines in which radially-disposed type-bars are arranged about a common printing point and move one at a time to the printing position.

These type-bars, especially in "front-strike" machines, are often closely arranged, so that, in rapid operation, there is liability of clashing, due largely to the fact that the type-bars may rebound from the basket or type-rest, upon returning to normal position, thus getting into the path of a subsequently-operated type-bar. Cushions have been provided at the type-rest to prevent such rebound.

An object of the invention is a cushion, for the purpose mentioned, which shall function more effectively, be of cheaper and more durable construction, and be less subject to deterioration by wear or distortion, than cushions heretofore employed.

Another object of the invention is an improved cushion, comprising a helix or helices, so set, and of such inelastic nature, as to absorb the force of the return-strokes of the type-bars, and thereby eliminate rebound of the latter. A feature of the invention is the shaping or setting together of the helix or helices to provide a broad surface for receiving and distributing the impact of the type-bars; thus to absorb the force thereof without undue distortion or wear of the cushion at the points where the bars strike the same.

Other features and advantages will hereinafter appear.

In the accompanying drawings,

Figure 1 is a view, in cross-sectional side elevation, through the platen, type-rest or basket, and type-segment of a front-strike typewriting machine, the type-bar, pivoted to the type-segment, being shown in normal position upon the type-rest.

Figure 2 is a front view of the type-rest or basket, hung from the top plate of the machine.

Figure 3 is a top plan view of the type-bar-rest or basket.

Figure 4 is a top plan view of one end of the type-bar-cushion.

Figure 5 is a top plan view of one end of a modified form of type bar cushion.

Figure 6 is a view, in cross section, of the cushion of Figure 4.

Figure 7 is a view, in cross-section, of the cushion shown in Figure 5.

Figure 8 is a perspective view of the helical coil of the Figure 5 cushion.

Figure 9 is a top plan view, partly in section, of a portion of the loops of the enveloped coils shown in Figures 2 and 4, in partial interlockment with each other.

The machine illustrated is of the front-strike variety. Type-bars 10, carrying types 11, lie horizontally in front of and below a platen 12, and are pivotally supported at their rear ends upon a curved fulcrum-rod 13, mounted in a slotted segment 14; the type-bars being operated by horizontal pull-rods 14^a, and provided with the usual returning springs (not shown). At their forward ends, the type-bars rest in a basket. The base of this basket is a segmental bar 15, having ears 16, whereby the segmental bar may be hung by screws 17 from the top plate 18 of the machine-frame, at the front of the latter. Set within the concavity of the segmental bar 15 is a cushion 19, against which the ends of the type-bars strike on return from the platen, and on which the type-bars rest except when operated.

In the form of the invention shown in Figures 4 and 6, the cushion 19 comprises two helical coils 20 and 21 of wire; which may be soft iron, soft brass or other suitable substance. The coils 20 and 21, preferably enclosed in canvas envelopes 22 and 23, respectively, are laid alongside each other lengthwise of the segmental bar 15. The turns or loops of one of the coils may interlock to some extent with the turns or loops of the other coil; the thin, flexible character of the canvas, or other selected material for the envelopes, if present, permitting of such interlockment. Thus laid alongside each other, the enclosed coils 20 and 21 are together enclosed in a single elongated envelope 24 of canvas or other material, which envelope is formed of a strip, folded laterally across the coils, and having its edges brought together, as at 25, to form a flange or lip, to receive pins 27, for securing the cushion to the segmental bar. Clips 25^a 110

may be employed to close the ends of the envelopes. The coils are so formed that adjacent loops or turns therein will rub on one another when the cushion is flexed by a type-
5 blow.

The two coils 20 and 21, being laid one forward of the other on the segmental bar, constitute a cushion of sufficient breadth to receive, and to properly distribute, the force
10 of the return-blows of the type-bars, without being unduly indented or disturbed by the bars. When the loops of one of the coils are set against the loops of the other, or are partially interlocked therewith, the cushion has
15 more stiffness or stability than otherwise; but is nevertheless sufficiently flexible to render the cushion wholly or nearly inelastic. A type-bar striking the cushion occasions a disturbance of the relative positions of the loops of the coils, the loops moving
20 on one another with a friction which causes the energy of the type-bar-blows to be absorbed by the cushion, and which opposes any elastic recovery of the cushion
25 when so bent or indented by the type-bar. In other words, when the type-bars strike the cushion, the latter is slightly flexed; but, owing to the binding and friction of the loops one up another in each coil, or, if the coils
30 lie against each other, or are interlocked, of the loops of one coil upon the loops of the other, the cushion does not at once recover, and the type-bar, instead of being thrown back, lies dead.
35 In the modification shown in Figures 5, 7 and 8, the cushion, instead of comprising two coils set one in front of the other on the segmental bar, comprises a single coil or helix 28 of flattened or elliptical cross-section. This coil is set in an envelope or
40 sheathing of canvas or other suitable material, similar to the envelope 24 of Figures 4

and 6, and having a flange or lip 29, by means of which it is secured by the pins 26 to the segmental bar 15.
45

The coil 28 is of such size, or rather is of such breadth from front to rear, as to provide, as in the case of the Figures 4 and 6 form of the invention, a wide seat for the type-bars. There being but one coil shown in the Figures 5, 7 and 8 modification of the invention, the friction and binding of one loop upon another is necessarily of adjacent loops in the same coil. As in the form of the invention first described, so in the Figures 5, 7 and 8 form of the invention, the cushion yields locally, or over a certain length thereof, to the return-stroke of the type-bars, and absorbs the force of such blows, but is so inelastic that the type-bar lies dead, instead of rebounding, on striking the cushion.
50

Variations may be resorted to within the scope of the invention, and portions of the improvements may be used without others.
55

Having thus described my invention, I claim:

1. A type-rest comprising a plurality of helices laid alongside and in partial interlockment with one another.
70
2. In a front-strike typewriting machine, a platen, a rigid segmental bar hung from the frame forward of the platen, a cushion comprising a plurality of helices laid alongside and in partial interlockment with each other on the segmental bar, and type-bars adapted to swing from the platen to a position in which their backs rest upon the several helices.
75

CORNELIUS B. CORCORAN.
